SLOTTED CENTERPIECE FIGURINE FOR NAPKIN DISPLAY AND HOLDING CANDLES, FLOWERS OR THE LIKE

Dorothy E. Maloy, 6250 E. Keim Drive,
Scottsdale, Ariz. 85253

Filed Nov. 9, 1973, Ser. No. 414,399

Term of patent 14 years

Int. Cl. D11—02

U.S. Cl. D29—23 E

FIG. 1 is a perspective view showing the front and one side of a slotted centerpiece figurine for napkin display and holding candles, flowers or the like;

FIG. 2 is a perspective view of the centerpiece shown in FIG. 1 showing the back and other side thereof; and

FIG. 3 is a fragmentary left side view of the centerpiece shown in FIG. 1.

I claim:

The ornamental design for a slotted centerpiece figurine for napkin display and holding candles, flowers or the like, as shown and described.
